[57] ABSTRACT

In order to reduce the possibility of producing cracks and other damages when lasting shoe uppers, the fore and back parts of the last are used as a mold core for shaping the upper, in combination with die means having concavities conforming to the desired shoe pattern. The last is of the type comprising two sections hingedly interconnected substantially intermediate its ends and near its bottom. The disclosed apparatus comprises a central portion for mounting the upper upside down, a front unit for shaping and tuning the front part of the upper, and a back unit for shaping the heel part of the upper.

APPARATUS FOR FITTING SHOE UPPERS

FIELD OF THE INVENTION

The present invention relates to the technique of fitting the fore and back parts of a shoe upper on a suitable last, with folding or turning of its projecting marginal connecting portions over the insole.

DESCRIPTION OF THE PRIOR ART

In most instances the back and front parts of an upper are assembled on two separate machines, although lasting machines are known to perform a simultaneous assembling operation. The methods involved are based on the application of carefully localized tractive efforts causing the upper to withstand considerable strain constituting a frequent cause of lasting failures and therefore of costly rejects. To perform this lasting operation successfully by means of recent technical methods, the lasting machine must be adjusted for each new upper, a job that only very skilled operators can perform, owing notably to the great variety of shoe materials and to the risk of improper stress distribution.

When the shoe styles change or in case of excessive size differences, it may become necessary to change the equipment.

At present, during the lasting of the front part of a shoe the upper covering the last is engaged between pincers which are subsequently reclosed. The number of such pincers may vary from three to 11 and each pair of pincers is adapted to assume any desired direction in space, in order to ensure an extremely accurate positioning of the upper.

In the case of a decorated and luxury upper this operation may be relatively long and delicate, for during the upper positioning the last is moved up and down in order to determine the possible upper reactions. In fact, in this type of fitting the upper does not slide on the last but, as soon as a contact is established, tension stresses and a certain elongation are observed at the points of contact.

When it is deemed that the upper is properly positioned, the last is "fitted" definitely in the upper by either actually raising the last or simultaneously lowering the assembling pincers.

This operation is necessary for eliminating pleats tending to develop on the upper as a consequence of the conversion of a flat surface into a volume.

It was proved that this method was attended by increments as high as 20 to 30 percent in the surface area, chiefly in the front part of the last. When bidimensional elongations of this magnitude (which may even be increased by the last style employed) are produced, cracks tend to develop in the upper and may cause this upper to be rejected.

Moreover, this lasting method involves the application of stresses definitely greater in the direction of the longitudinal axis of the upper. Therefore, the lateral forces that should be applied to the upper are not sufficient and the shape is far from having the desired fidelity, notably in the top portion of the upper. As a result, the upper does not adhere to the concave portions of the last.

At present, the lasting of the rear part of an upper is performed only after preshaping the counter on a metal die by using an inflatable bladder or a the like.

According to the specific type of counter utilized (stiffening counter softened by using suitable solvents or by the action of heat), the preshaping operation is designed as a rule to impart to the rear part a shape approximating the finished shape obtained after the final lasting operation.

This preshaping operation, also intended to impart a sufficient malleability to the stiffening counter, is accomplished either by accelerating the rate of solvent evaporation (in order to increase the stiffness of the counter if the latter is initially too soft) or by heat-softening the counter if it is deemed too hard.

Then the sides are fitted by using a machine adapted to fold the projecting marginal portions of the upper over the insole to which these portions are caused to adhere by cementing or nailing.

It may be noted that in the conventional technique only the lasting of the fore part of the upper is attended by a tractive force exerted on the upper, the lasting of the back or heel part requiring mainly compressive forces.

It is apparent that the fitting and lasting of the fore and back parts of the upper of a shoe involves many operations, different machines, considerable handling and skilled hands.

It is the primary object of the present invention to avoid the various inconveniences mentioned hereinabove and more particularly to improve the quality of industrial shoes while reducing the risk of damaging the upper while also shortening the lasting time.

SUMMARY OF THE INVENTION

In accordance with this invention we utilize as a mold core the fore and back portions of the assembling last for shaping the upper, in combination with die members having concavities which conform to of the pattern of the shoe to be produced.

Thus, the upper is deformed under the best possible conditions and adheres perfectly to the corresponding portions of the last.

When the upper has thus been deformed and caused to conform exactly to the shape of the fore and back portions of the last, the marginal connecting portions are folded over according to conventional methods.

Preferably, the last utilized for carrying out this invention is of the type described in French Pat. No. 2,131,098. In this case, after lasting the toe and heel portions of the shoe, the last is opened in order to generate essentially longitudinal stresses in the upper and thus improve the shaping of the central portion of the upper on the last and more particularly the top surface thereof.

An apparatus for carrying out this method, in accordance with our invention, comprises essentially:

a central assembly adjustable in the longitudinal direction for properly placing the last in its upside-down position;

a front assembly for lasting the fore part of the upper, which comprises a fixed but adjustable die provided with a pair of movable jaws for folding the projecting marginal portions of the upper by means of a presser element such as a cylinder-and-piston unit or jacks capable of sinking the fore part of the last into the die, and also by means of other cylinder-and-piston units or jacks for pressing the upper edges against the die edges until the last has been properly sunk, and

a rear assembly for lasting the back or heel part of the upper, which comprises a die displaceable to press same against the last and provided with another pair of movable folding jaws.

This machine is constructionally relatively simple and capable of giving very satisfactory results; it can be easily incorporated into an automatic industrial shoe-making line.

In a preferred embodiment the central support is connected to a cylinder-and-piston unit adapted to drive this support away from the die coacting with the fore part of the last, during the deformation of the corresponding portion of the upper in order to impart longitudinal stresses to the upper simultaneously with the transverse stresses resulting from such deformation.

The invention will be better understood from the following description given with reference to the accompanying drawing illustrating diagrammatically by way of example a typical embodiment of the apparatus according to our invention. In the drawing:

BRIEF DESCRIPTION OF THE DRAWING

FIGS. 1 and 2 are side-elevational views showing in section the lasting apparatus according to this invention before and during the upper deformation;

FIGS. 3, 4, 5 and 6 are sections taken along the line 4-4 of FIG. 2, showing some of the various steps of the upper-deformation process;

FIG. 7 is a top plan view showing on a larger scale the assembly provided for shaping the back part of the upper; and

FIG. 8 is a section taken along the line 8-8 of FIG. 7.

DESCRIPTION OF THE PREFERRED EMBODIMENT

The apparatus illustrated diagrammatically in the drawing comprises three main assemblies, i.e., a central assembly or unit 2, a front assembly 3 for shaping the fore or toe part of the upper, and a rear assembly 4 for shaping the heel or back part of the upper.

The central assembly 2 comprises a slide 5 movable longitudinally on a transversely movable carriage 6. This carriage is adapted to travel on a track 7 rigid with a fixed frame structure 8. Of course, means (not shown) are provided for locking the carriage 6 against motion during the upper-shaping operation. The slide 5 carries a fixed rod 9 and a pivot rod 10 fulcrumed at 12 and connected to the piston rod of a control unit or jacks 13 of the piston-and-cylinder type. The aforesaid rods 9 and 10 are adapted to be inserted into corresponding bores formed in the back portion of a last 14.

Preferably, this last 14 is of the type described and illustrated in the French Pat. No. 2,131,098 mentioned hereinabove. It is locked in position by altering the relative spacing of the pair of rods 9, 10 under the control of jack 13.

Finally, the slide 5 is connected to another fluid-actuated cylinder-and-piston unit or jack 31 adapted to shift this slide 5 longitudinally in relation to the assembly 3 for shaping the toe or fore part of the upper.

The front assembly 3 comprises a die 15 carried by a support 16 fulcrumed at 17 to a base plate 11 vertically adjustable in relation to the frame structure 8. This assembly 3 further comprises a plurality of cylinder-and-piston units or jacks 18 disposed all around the die 15 and adapted to press the marginal portions of the

upper against this die, another fluid-actuated unit or jack 19 adapted to engage the toe end of the upper, and finally a cylinder-and-piston unit or jack 20 for actuating a pair of folding plates or jaws 22.

The rear assembly 4 intended for shaping the back or heel portion of the upper comprises a die 23 fitted in a holder 24 secured to the outer end of the piston rod of a cylinder-and-piston unit or jack 25 having its cylinder carried by a support 21 movable longitudinally in relation to the frame structure 8 of the apparatus. The holder 24 is also rigid with the cylinder of another jack 26 having its piston rod adapted to actuate a pair of folding plates or jaws 27.

The dies 15 and 23 are produced by casting on a pattern of the desired article a self-hardening polymer of the type developing a polyaddition or polycondensation reaction process. These exothermic reactions permit of producing dies without any destruction of materials, such as leather, constituting the pattern on which the dies are molded. The exothermic reaction may be adjusted, e.g., by modifying the catalyst percentage.

Prior to any operation, the apparatus according to this invention is adjusted in conformity with the last to be used therein. The lower face of the insole 29 fitted on the last, i.e., on the upper face of this last as seen in FIGS. 1 and 2, is first made level with the upper face of die 23 by adjusting nuts 28 on the screw-threaded rods 9 and 10. Then, the base plate 11 is adjusted vertically while the support 16 is adjusted by pivoting same about its fulcrum pin 17 so that the top surface of die 15 becomes coplanar with the face of insole 29 bearing against the last, then in its closed position.

It should be noted that these various adjustments are required only when changing from one last to another.

When the adjustment operations are completed, the insole 29 is fitted to the last 14. The fore part of the upper 30 is placed on the die 15 and retained thereon by means of clamping jacks 18, as shown in FIG. 3. Slide 5 is moved by means of jack 31 toward the assembly 3, as shown by arrow 34; then the last 14 with its insole 29 is introduced into the upper and mounted on the pair of rods 9 and 10, and locked in position by means of jack 13. Slide 5 is moved back toward the assembly 4 by a jack 31 (arrow 35), approaching its initial position to an extent depending of course on the shoe size of the last.

This movement of the slide is not absolutely necessary but facilitates the shaping of the top portion of the upper. Upon completion of these operations, performed manually, the shaping and fitting of the shoe elements can take place in a fully automatic manner.

The jack 19 is supplied with fluid under pressure to that its piston rod will bear against the toe part of the last 14 for pressing same into the die 15. The fore part of the last 14 will thus engage the confronting portion of upper 30 and thus cause the latter to conform to the concavity of die 15. During this movement the jacks 18 restrain the slippage of the marginal portions of the upper in the direction of the arrows 32 of FIG. 4. When the fore part of the upper is shaped and conforms perfectly to the shape of the die, the piston rods of units 18 are retracted while the jaw-actuating jack 20 is supplied with fluid under pressure for actuating the folding plates 22. In conventional fashion these plates 22 fold the forward parts of the marginal connecting portions 33 of upper 30 over the insole 29 until they assume the

position illustrated in FIG. 6, in which they are maintained by cementing or otherwise.

At the same time as the fore part of the upper is shaped, or during a subsequent operation, the jack 25 is supplied with fluid in order to move the holder 24 in the direction of the arrow 34 of FIG. 2 and bring the die 23 against the upper 30, engaging the confronting heel portion of last 14. As a result, the back part of the upper is shaped between the last 14 and die 23 as shown in FIG. 8. The jaw-actuating jack 26 is then operated to cause the folding plates 27 to turn the rear parts of the marginal portions 33 around the back portion of the insole 29.

Under these conditions, the fore and back parts of the shoe upper are shaped and fitted, and the central portion thereof is shaped by simply opening the last 14 as described in the aforementioned French Pat. No. 2,131,098.

Upon completion of the upper-shaping operation performed by means of this apparatus, the carriage 6 is moved along its track toward other stations where complementary assembling operations are accomplished.

Although a specific embodiment has been described herein with reference to the accompanying drawing, it will readily occur to those conversant with the art that various modifications may be imparted thereto without departing from the spirit and scope of the invention as set forth in the appended claims.

What we claim as new is :

1. An apparatus for fitting a shoe upper around a last, comprising:
  - a supporting structure;
  - a central assembly on said structure provided with mounting means for holding a last in an inverted position;
  - a front assembly on said structure adjacent said central assembly including movable first die means with a first concavity matingly confronting a fore part of the mounted last, releasable clamping means on said first die means for engaging opposite marginal portions of a forward part of a shoe upper spanning said first concavity, and first pressure

means engageable with said fore part of the last for forcing same into said first concavity to deform said forward part of the shoe upper, said first die means being provided with first jaw means operable to fold said marginal portions of said forward part over the sole of the inverted last upon release of said clamping means; and

a rear assembly on said structure adjacent said central assembly including movable second die means with a second concavity confronting a back part of the mounted last and second pressure means for displacing said second die means toward said central unit to deform a rear part of the shoe upper between said back part of the last and said second concavity, said second die means being provided with second jaw means operable to fold opposite marginal portions of said rear part of the shoe upper over the sole of the inverted last.

2. An apparatus as defined in claim 1 wherein said central assembly is shiftable on said structure toward and away from said front assembly, further comprising drive means for so shifting said central assembly.

3. An apparatus as defined in claim 2 wherein said central assembly comprises a carriage slidably supporting said mounting means and carrying said drive means, said structure forming a track for said carriage extending transversely to the direction of shift of said central assembly.

4. An apparatus as defined in claim 3 wherein said first and second pressure means and said drive means are respective fluid-operated jacks.

5. An apparatus as defined in claim 1 wherein said clamping means comprises a set of fluid-operated jacks.

35 6. An apparatus as defined in claim 1 wherein said first and second jaw means are provided with fluid-operated actuators.

7. An apparatus as defined in claim 4 wherein said front assembly includes a pivotal mounting for said first die means enabling same to be swung about a horizontal axis.
